(57) **CLAIM**

The ornamental design for an avionics display with icon, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front view of a portion of an avionics display with icon showing a first embodiment of the claimed design; and, FIG. 2 is a front view of a portion of an avionics display with icon showing a second embodiment of the claimed design. The outermost broken line rectangle illustrates a portion of an avionics display and forms no part of the claimed design. The remaining broken lines illustrate portions of the graphical user interface and form no part of the claimed design.
